UNITED STATES PATENT OFFICE.

FREDERICK M. HARMON, OF CLEVELAND, OHIO.

FEED-WATER HEATING AND PURIFYING APPARATUS.

1,006,479.

Specification of Letters Patent.

Patented Oct. 24, 1911.

Application filed February 18, 1911. Serial No. 609,459.

To all whom it may concern:

Be it known that I, FREDERICK M. HARMON, a citizen of the United States, residing at Cleveland, in the county of Cuyahoga and State of Ohio, have invented certain new and useful Improvements in Feed-Water Heating and Purifying Apparatus, of which the following is a specification.

My invention relates in general to feed water heaters and purifiers, and has for its principal objects; the provision of an improved feed water purifier which is entirely closed in order to prevent the spilling of the contents thereof; the provision of an improved feed water heater and purifier composed of sections detachably held together so that the parts may be readily assembled and put in place, and as readily taken apart for cleaning; the provision of improved means for securing together and supporting the sections of a sectional feed water purifier; and in general the provision of a device of the character specified which is simple in construction and effective in operation and particularly applicable for use on marine boilers. These together with such other objects as may hereinafter appear or are incidental to my invention, I attain by means of a construction illustrated in preferred form 30 in the accompanying drawings, wherein—

Figure 1 is a longitudinal section through a portion of a boiler, showing my improved purifier in section;

Figure 2 is an enlarged plan view of a portion of the purifier;

Figure 3 is an enlarged section on the line III—III of Figure 1, and

Figure 4 is an end view of a boiler showing the location of the various parts.

Referring to Figure 1 of the drawings, it will be seen that I have shown a portion of a boiler 1 having the usual flues or boiler tubes 2 and provided with the stay bolts or tie rods 3—3 to support the boiler head 4. Suspended within the boiler shell from two of the tie rods 3—3 is the feed water heater and purifier which is preferably composed of three cylindrical sections 5, 6 and 7—detachably held together in a manner to be described. The sections fit into rings or joining members 8 and 9 and rings or heads 10 and 11, all of which are provided with a plurality of slots 12 adapted to receive the through bolts or rods 13 which alternately

extend in opposite directions and serve to 55 hold and bind the sections and rings the one to the other. This will be seen on inspection of Figures 2 and 3. It will be noted that the rings are provided with sloping flanges which insure a rigid and tight joint when 60 the sections are secured together. The rings 8 and 9 are also provided with oppositely disposed baffle plates 14 and 15 to agitate the water as it passes from one end of the cylinder to the other, and separate and 65 deposit the solids.

Water is admitted to the cylinder from the water feed pipe 16 through an inlet in the head 11, and passes into the boiler feed pipe 17 through an outlet in the head 10. 70 The heads are provided with pockets 18 and 19 adjacent the inlet and outlet openings which are arranged to normally keep the height of the water somewhat above center line. The pocket 19 also serves to agitate 75 the incoming water. A pony or make-up feed 16' is provided so that hot water may be supplied to the cylinder from a source other than the main feed 16.

Steam from the boiler has access to the 80 interior of the cylinder by means of openings 20 and 21 and is utilized to heat the water and to blow out the mud and scale which has deposited on the bottom of the cylinder. I have provided a number of outlet openings 22 in the bottom of the cylinder which are connected to a blow off pipe 23 leading out of the boiler and provided with the usual blow off valve, (not shown). On opening the blow off valve the live steam 85 blows out the mud and scale through the discharge pipe 23, the pockets 18 and 19 serving as guards to prevent the entrance of any of the deposit into the water feed 16 and boiler feed 17.

The cylinder is suspended from the tie rods 3—3 by means of a number of hangers (see Figure 3) composed of two members 25 and 26 adapted to embrace the cylinder and the tie rods and secured by nuts 27. 100 It will be obvious that the hangers are easily put in place and as easily detached.

It is to be noted that by the provision of the slotted rings and the through rods 13, the sections are securely and rigidly bound, 105 the one to the other, into a firm structure, and are, at the same time, readily taken apart for inspection and cleaning. The

parts are also easily assembled and their installation facilitated by this construction.

Boiler feed pipe 17 extends to the bottom of the boiler thereby assuring a free circulation.

By providing an entirely closed cylinder, I prevent any spilling over of the contents and the consequent depositing of the mud and scale on the adjacent boiler tubes, which 10 is one of the chief disadvantages incident to the use of purifiers of the usual open box type on marine boilers. One of the advantages of providing a cylindrical purifier is that there are no corners where the 15 mud and scale will deposit and stick during the blowing out operation. The pockets 18 and 19 are a simple means for permitting the blowing out of the purifier without shutting down the boiler. Other advantages 20 will occur to those familiar with the art.

Having thus described my invention and illustrated its use, what I claim as new and desire to secure by Letters Patent is the following:

25 1. A feed water purifier comprising in combination, a body portion, an inlet opening, an outlet opening, pockets on the inside of the body portion adjacent each opening, means for admitting steam into the 30 body portion, a blow-off discharge opening, and means for supporting the body portion, the said pockets being adapted to protect the inlet and the outlet openings from mud and scale when steam is admitted to blow out 35 the body portion.

2. A feed water purifier comprising in combination, a body portion composed of sections, a plurality of joining members fitting into the sections, baffle walls on some 40 of the joining members, an inlet, an outlet, a steam inlet, a blow off discharge outlet, a pocket adjacent the first mentioned inlet, a pocket adjacent the first mentioned outlet, said pockets being on the inside of the 45 body portion and adapted to protect the inlet and the outlet openings from mud and scale upon admitting steam to blow out the body portion, and means for tying the joining members together.

50 3. A feed water purifier comprising in combination an entirely closed body portion, a feed water inlet, a boiler feed outlet, baffles for agitating the water, a steam inlet, a discharge blow off outlet, a guard 55 for the feed water inlet, a guard for the boiler feed outlet, said guards being adapted upon blowing out the purifier to prevent the entrance of deposits into the water feed inlet and boiler feed outlet, and means for supporting the body portion in the boiler.

4. In a boiler, a substantially horizontal cylindrical heating tank, having a perforated top, means for supporting the tank in the normal steam space of the boiler, a 60 blow out pipe extending from the lower

portion of the tank to the exterior of the boiler, a feed water inlet to the tank extending from the exterior of the boiler, and a feed water outlet leading from the tank to the interior of the boiler.

5. In a boiler, a cylindrical heater tank in the upper portion of the boiler and extending longitudinally thereof, an inlet from the exterior of the boiler leading into one end of the tank, an outlet leading from 75 the other end of the tank into the boiler, a plurality of pipes leading from different points along the lower portion of the tank, and a common blow out pipe connected to such pipes and leading to the exterior of 80 the boiler.

6. A feed water heater comprising a horizontal cylindrical tank, means for admitting live steam to the tank, a blow out pipe leading from the lower portion of the tank, 85 a feed water inlet to the tank, an upwardly opening pocket in one of the heads of the tank, and a feed water outlet leading from such pocket.

7. A feed water heater comprising a horizontal cylindrical tank, means for admitting live steam to the tank, a blow out pipe leading from the lower portion of the tank, a downwardly opening pocket in one of the heads of the tank, an upwardly opening 95 pocket in the other head, a feed water inlet to the downwardly opening pocket, and a feed water outlet from the other pocket.

8. A feed water purifier comprising in combination a cylindrical body portion composed of sections, joining members for the sections, baffles on the joining members, a plurality of slots in the joining members and a plurality of oppositely disposed through rods mounted in the slots for detachably securing the joining members together.

9. In a boiler, a feed water heater and purifier comprising in combination, a cylindrical sectional tank in the upper portion of the boiler and extending longitudinally thereof, joining members for the sections, oppositely disposed baffle plates in the joining members, an inlet leading from the exterior of the boiler into one end of the tank, an outlet leading from the other end of the 110 tank into the boiler, a downwardly opening pocket adjacent to the outlet and a blow out pipe leading from the tank to the exterior of the boiler.

10. The combination of a feed water purifier and heater comprising a tank composed of a plurality of sections, joining members detachably fitting into the sections, a baffle plate on one of the members, an inlet, an outlet, protecting guards for the inlet and the 125 outlet, and means whereby the foreign matter deposited is blown out of the tank.

11. In a boiler provided with stay rods extending between the heads of the boiler; a sheet metal sectional heater removably sup-

ported upon the rods in the normal steam space of the boiler, joining members for the sections, baffle plates in the joining members, an inlet from the exterior of the boiler leading into one end of the tank, an outlet leading from the other end of the tank into the boiler, and a blow-out pipe leading from the tank to the exterior of the boiler.

12. A feed water heater comprising, in combination, a horizontal tank composed of sheet metal sections, means for admitting live steam to the tank, a blow-out pipe leading from the lower portion of the tank, a feed water inlet to the tank, an upwardly opening pocket inside one of the heads in the tank, and a feed water outlet leading from said pocket.

13. A feed water heater comprising a horizontal sectional tank means for admitting live steam to the tank, a blow-out pipe leading from the lower portion of the tank, a downwardly opening pocket inside one of the heads of the tank, an upwardly opening pocket inside the other head of the tank, a feed water inlet to the downwardly opening pocket, and a feed water outlet from the other pocket.

14. A feed water heater comprising in combination, a body composed of sheet metal sections, joining members between the sections, said joining members being castings provided with integral baffle plates and

means for securing the joining members together substantially as subscribed.

15. In a boiler, a sectional heater tank in the normal steam space of the boiler and extending longitudinally therein, joining members in the sections, said joining members being provided with integral baffle plates oppositely disposed one to the other, an inlet leading into one end of the tank from the exterior of the boiler, an outlet leading into the boiler from the other end of the tank, a plurality of pipes leading from different points along the lower portion of the tank and a common blow out pipe connected to such pipes and leading to the exterior of the boiler.

16. A feed water heater comprising in combination, a horizontal tank composed of sheet metal sections, means for admitting live steam to the tank, a blow-out pipe leading from the lower portion of the tank, a downwardly opening pocket inside one of the heads in the tank, a feed water inlet opening into said pocket, and a feed water outlet.

In testimony whereof, I have hereunto signed my name in the presence of the two subscribed witnesses.

FREDERICK M. HARMON.
